UNITED STATES PATENT OFFICE

VICTOR KULEBAKIN, OF MOSCOW, RUSSIA

DISTURBANCE ELIMINATOR

Application filed March 29, 1923, Serial No. 628,677, and in Russia July 25, 1922.

The reception of wireless telegraphic and telephonic reports is influenced on aircraft, apart from other considerations, mainly by two factors, viz.

- 5 1. By the external noises, which are produced by the working motors, the rotation of the air screws, the vibration of the bracing wires, etc.
 10 2. By the disturbing action of the system which serves for the ignition of the combustible mixture in the motors and consists of high tension magnetos or other apparatus, plugs and conductors.

For the purpose of protecting this wireless telegraphic and telephonic reception from external noises special helmets with ear flaps, which lie close against the head and ears, also special so called internal telephones are used, these latter being inserted in the external auditory passage. This enables the effect of the secondary noises of the working motors to be kept away from the sounds to be received. Nevertheless the disturbing effect of these secondary noises is very great. For 25 this reason the calls and messages to be picked up must be sufficiently powerful to enable the receiver on the aircraft to pick them up accurately and therefore it is necessary to intensify them.

30 To overcome the disturbing action of the electrical ignition apparatus system of aircraft, entirely different means are necessary, as the disturbing effect is due partly to magnetic induction but mainly to the radiation 35 of the magnetic waves in the formation of the spark at the plug during ignition.

The present invention is based on the consideration that it is not so very important to screen off the receiving apparatus or protect it in the same way, but what should be done is to weaken the radiation of the electro-magnetic energy of the ignition system considerably during the formation of the spark.

45 This is effected according to the present invention by the use of conductors which possess a great ohmic resistance (f. i. 1,000,000 ohms) uniformly distributed over its whole length, by which the ignition apparatus is 50 connected to the motor. The damping re-

sistance must be in the circuit to be damped. But this circuit is not quite fixed, for the reason that the capacity of the ignition current lines with relation to the metallic mass of the motor is distributed over the whole length. 55 Therefore, the damping resistance of each line must also be distributed over its whole length. Such conductors may consist of thin conductors of metallic alloys of great ohmic resistance. By using conductors with a great 60 ohmic resistance the degree of damping of the oscillations produced when the spark is formed can be considerably increased and in this way the electro-magnetic energy which is to be eliminated can be also reduced. 65

In the drawings, Figure 1 shows a constructional example of the invention illustrating a six cylinder motor with a corresponding ignition apparatus. Figure 2 discloses a portion of a chain conductor in accordance with this invention. Fig. 3 is a diagrammatic showing of the equivalent electrical effects of the use of an oxidized chain conductor in the ignition circuit.

The following is a statement of the theory 75 of operation which is believed to be correct:—

The action of a continuous conductor of about one million ohms can be further increased, when the conductor is replaced by an 80 oxidized chain. The resistance characteristic of such a chain is a totally different one from that of a continuous conductor. An oxidized chain conductor constitutes the equivalent of and has the same effect as a 85 net work of condensers, self-inductors and resistances, as shown diagrammatically by Fig. 3.

The contact surfaces of chain links present on account of their oxidation not only a high 90 resistance R, but have also a capacity action, as indicated diagrammatically by reference characters K in Fig. 3 of the drawings. The chain links also constitute small self inductors, which is shown diagrammatically by 95 reference characters L in Fig. 3 of the drawings. These links together with the metallic motor mass, M constitute small condensers which are schematically illustrated in Fig. 3 by reference character C. Such a chain, 100

therefore, forms a great number of oscillation circuits, which serve to dampen the ignition spark itself after its inception. These inductances and capacities are of small value and make the frequency of the ignition circuit 5 so high that it varies considerably from the frequencies of the radio receiving circuits, and, therefore, does not disturb or interfere with proper reception. The action of the invention is increased if the external metallic 10 parts of the plugs and the motor casing are connected to the ignition apparatus by good conductors at certain points, as shewn in the drawing. A connection of this kind has given 15 a still better working.

In Figure 1 the dotted conductors (*a*) are intended to denote chains of iron with an oxidized outer surface or other conductors with great resistance uniformly or intermittently distributed over its whole length, 20 which chains are diagrammatically indicated in Fig. 2. *b* is the connection of the external metallic parts of the plugs to the ignition apparatus and *c* the conductor for connecting certain points of the motor casing to 25 each other and to the ignition apparatus. This is for preventing the occurrence of any electrostatic potentials.

Having now described my invention, what 30 I claim as new and desire to secure by Letters Patent is:

1. Means associated with the electric ignition system of an internal combustion engine for preventing any oscillations likely 35 to interfere with radio reception, comprising conductors in said ignition system each having an ohmic resistance of about one million ohms distributed throughout its length, each conductor comprising a relatively large number of parts loosely engaging one another.

2. Means associated with the electric ignition system of an internal combustion engine for preventing any oscillations likely to interfere with radio reception, comprising 45 connections in said ignition system having an ohmic resistance of about one million ohms distributed throughout their lengths, said resistance consisting of a chain composed of metallic links the outer surfaces of which 50 are oxidized.

3. Means associated with an electric system generating disruptive discharges for preventing any oscillations likely to interfere with radio reception comprising a conductor consisting of a plurality of distinct, 55 loosely connected elements, the outer surfaces of which are oxidized.

4. Means associated with an electric system generating disruptive discharges for preventing any oscillations likely to interfere with radio reception comprising a chain conductor consisting of a plurality of links, the outer surfaces of which are oxidized.

5. Means associated with an electric system generating disruptive discharges for pre-

venting any oscillations likely to interfere with radio reception comprising a conductor consisting of a plurality of elements, the outer surfaces of which are oxidized, and contact between such elements being established through such oxidized surfaces, whereby the conductor has the same effect as a net work of inductances and small capacities.

6. Means associated with an electric system generating disruptive discharges for preventing oscillations likely to interfere with radio reception, comprising a conductor consisting of a relatively large number of elements inter-engaging with one another, the outer surfaces of each of said elements being coated with a compound containing an electrically conductive substance.

In testimony that I claim the foregoing as my invention, I have signed my name.

VICTOR KULEBAKIN.
